FORNIA.

PROCESS FOR THE SYNTHETIC PRODUCTION OF NITROGEN COMPOUNDS.

1,206,155.

Specification of Letters Patent. Patented Nov. 28, 1916.

Application filed May 3, 1915. Serial No. 25,608.

To all whom it may concern:

Be it known that we, PAUL A. STARKE and ERIC A. STARKE, citizens of the United States, residing at Berkeley, in the county of 5 Alameda and State of California, have invented certain new and useful Improvements in Processes for the Synthetic Production of Nitrogen Compounds, of which the following is a specification.

10 Our invention relates to the synthetic production of nitrogen compounds, such as cyanids or cyanogen compounds and ammonia, and more particularly to a process of obtaining the same from methane. The process is 15 based upon our discovery that by using methane as the source of production the catalyst may be free of carbon.

We are aware of synthetic processes in 20 which artificially prepared gases, mixed with nitrogen, are passed through a heated catalytic mass. Such gases have always been composed of hydrogen and carbon monoxide with varying proportions of hydrocarbon gases, and it has been essential that carbon 25 and other reducing agents, such as alkali metals, boron, etc., be present in the catalytic mass.

We have found that methane may be used 30 as the source of production of the cyanid without the presence of carbon or other reducing agents in the catalytic mass, as said gas itself furnishes the necessary carbon for the reaction. In this discovery lies the 35 advantage of our process, in that we are able to utilize natural gas and commercial alkalis as the source of production, with the result of both cheapening the process and increasing the production.

We may here state that we employ the 40 term methane generically, to cover and include all forms of natural gas, whether petroleum gases, or marsh gases, or any natural gas of the paraffin series, which are, as is well known, simply impure forms of meth-

45 ane.

Our process consists, in general, in first mixing methane with nitrogen; then preparing the catalytic mass, then passing the mixture of methane and nitrogen through the 50 catalytic mass at suitable temperature for the desired reactions; and then recovering from the catalyst the nitrogen compounds. These steps, in their order, will now be more fully explained.

The methane may be any natural gas of 55 the paraffin series. The nitrogen may be had from any source and produced in any suitable manner. In practice we use atmospheric nitrogen, by simply mixing air with the methane. The proportion of nitrogen to 60 be used with the methane may vary, but we find that a mixture of about equal volumes is best, as in such proportion its activity as a reducing agent is considerably increased. The catalytic mass is best a mixture of an 65 alkali or an alkali metal salt, an alkaline earth, and a metal of the iron group. The alkali may, for example, be sodium or potassium oxid or carbonate, or the salt may be potassium or sodium sulfate, or these 70 alkalis and salts may be mixed. The alkaline earth may be the oxid of calcium, barium or magnesium, or these may be mixed. The metal may be iron or aluminum, either in the metallic form or in combination, such as 75 sodium aluminate, sodium iron oxid, or barium aluminate or iron oxid. We find that when the catalytic mass contains only an alkali or a mixture of alkalis or salts of alkali metals the amount of cyanid is small, and 80 we further find that even when, in addition, an alkaline earth is incorporated in the catalytic mass, the yield of cyanid though greatly increased, is still insufficient to warrant commercial production. Finally, we 85 find that when the metals comprising the iron group, that is, any salts of iron, nickel, cobalt, chromium or aluminum are also present in the catalyst, the yield is so materially influenced as to place the process on 90 a commercial basis. It makes little difference in what form the metal is present, that is, whether it be in the metallic state or in some form of chemical combination.

As an alkaline salt we prefer the carbonates, such as sodium or potassium carbonates. Chlorides can also be employed as these transpose with the alkaline earth cyanids. If sulfids or sulfates are used, sulfocyanids result. In all the reactions, carbon, as such, in the 100 catalytic mass is not essential to the process, for the reason which we have heretofore stated, namely, that the methane is itself the source of carbon supply for the cyanid. The presence of carbon in the catalytic mass may be, 105 however, a benefit, but for a different reason, namely, that it may render the mass more porous and thus permit the intimate.

contact of the gas throughout the body of the catalyzer. Its action here is not, however, a primary one. The temperature under which the reactions take place may vary 5 widely. As usual with this class of synthetic processes the temperatures are high, and without meaning to limit ourselves we may state that we have found that a minimum temperature of about 600 degrees C. is 10 required to bring about the reaction. The percentage of cyanid formed appears to increase in direct proportion to the rise in temperature. After the reaction is complete, the cyanogen compounds are recovered from 15 the catalytic mass. We find that this can be done by lixiviation. They may then be properly refined. Or the cyanids in the catalytic mass may be decomposed by superheated steam into formates and ammonia, 20 and the latter recovered by condensation.

In carrying out our process we will now give a concrete example, in connection with a simple form of apparatus, though it is to be understood that both in the process and apparatus, various modifications and changes 25 may be made within the scope of our invention or discovery.

In the accompanying drawing the figure represents a form of retort in which the 30 reactions may take place.

1 is a shell the walls of which are of suitable refractory material. Within the shell is a retort 2 with the top of which communicates a feed pipe 3 which passes in 35 through the top of the shell and has a valve 4. From the bottom of the retort issues a delivery pipe 5 having a valve 6, said pipe being adapted to discharge the contents of the retort into a suitable receptacle, say, for 40 example, a car 7.

8 is a gas inlet pipe to the retort, said pipe extending down within the retort nearly to its bottom.

9 is a gas outlet pipe from the retort. 45 10 is a supply pipe for heating gas, and 11 is a ring of Bunsen burners within the base of the shell and adapted to heat the retort.

A concrete example of the process is as 50 follows:—We first prepare the catalyzer. We take—

Calcined magnesium oxid..... 65 parts.
Potassium carbonate..... 25 parts.
Metallic iron..... 10%

55 and these we mix in the following manner: The potassium salt is dissolved in the smallest possible quantity of water. The iron is dissolved in the smallest possible quantity 60 of acetic acid. The acetate solution is then added to the calcined magnesium oxid, and when these have been thoroughly mixed, the potassium solution is added. A slight effervescence takes place owing to the acetic acid. 65 The mass is thoroughly mixed and then

dried in an oven. After the paste has been sufficiently hardened it is calcined, in order to decompose the acetates, leaving the mass resembling porous red clay or infusorial earth. This catalytic mass we then supply 70 to the retort 2. Heat is then turned on and the temperature of the mass is raised to and is maintained at, at least, 600 degrees C. We prepare a mixture of nitrogen and methane using, in practice, natural gas of 75 the paraffin series. The nitrogen may be had from any source; in practice we use atmospheric air. The mixture is composed of about equal volumes of natural gas and nitrogen. The use of atmospheric air in 80 this respect is highly advantageous in that its oxygen will unite with the carbon of the methane to form in the mixture carbon monoxid, nitrogen, hydrogen and methane. Also the difficulty and expense of preparing 85 pure nitrogen are obviated, and other than drying and removing the carbon dioxide by passing through lime filters the air can be used at once. Furthermore, with methane a thorough and permanent mixture 90 of any volume can be made with air, while with condensable hydrocarbons homogeneous mixtures with air are not readily produced. Finally, it may be noted that the permanent hydrocarbon gases, such as the 95 marsh gas series, contain more hydrogen than any other known combination of hydrogen, and this high percentage of hydrogen renders such gases peculiarly adaptable for the formation of cyanogen compounds. 100 This mixture we pass in through the pipe 8 and discharge it into the bottom of the heated catalytic mass within the retort. It rises through said mass and the reactions take place therein forming the cyanogen 105 compounds. Instead of using iron in the form of acetate, finely divided metallic iron may be used. The increase in the percentage of cyanid formed is not only in proportion to the rise in temperature but also 110 in proportion to the division of the iron throughout the catalytic mass. Thus, we have obtained yields as high as 30% sodium cyanid when the iron is in a very fine state of division. When the iron is used in the 115 form of acetate it is most efficiently spread throughout the mass so that it is in a fine state of division. The gas after passing through the catalyzer flows off through the pipe 9, and may be recovered for use again. 120 When the reaction is complete, the catalyzer is delivered from the retort through the pipe 5 into the car 7. By the car it is taken to a convenient place for the recovery of the cyanids. This is done in any suitable 125 manner, in practice, by lixiviation. After the extraction of the cyanids, the catalyzer after having its loss of alkali replaced can be returned to the retort, or fresh catalytic masses may be used. 130

We claim:—

1. The process for the synthetic production of nitrogen compounds which consists in first making a mixture of methane and nitrogen; then passing said mixture through a heated catalytic mass devoid of carbon as a chemical reactive agent to form therein cyanogen compounds; and, finally, recovering the nitrogen compounds from said mass.
- 10 2. The process for the synthetic production of nitrogen compounds which consists in first making a mixture of methane and nitrogen; then passing said mixture through a heated catalytic mass devoid of carbon as a chemical reactive agent and composed of alkaline substances with which is mixed a metal of the iron group, to form therein cyanogen compounds; and, finally, recovering the nitrogen compounds from said mass.
- 15 3. The process for the synthetic production of nitrogen compounds which consists in first making a mixture of methane and nitrogen; then passing said mixture through

a heated catalytic mass devoid of carbon as a chemical reactive agent and composed of a mixture of alkalis, alkaline earths and a metal of the iron group to form cyanogen compounds in said mass; and, finally, recovering the nitrogen compounds from said mass.

25

4. In the process for the synthetic production of nitrogen compounds by catalysis, that step which consists in subjecting a mixture of methane and atmospheric air, under a temperature not lower than 600 degrees centigrade, to a catalytic agent devoid of carbon as a chemical reactive agent.
